Patented Dec. 5, 1972

225,386

ELECTRIC DRY SHAVER

Hermann R. Schaefer, Bridgeport, Conn., assignor to
Sperry Rand Corporation, New York, N.Y.

Filed Nov. 16, 1970, Ser. No. 25,996

Term of patent 14 years

Int. Cl. D28—03

U.S. Cl. D95—3

Fig. 1

Fig. 2

Fig. 3

Fig. 4

Fig. 5

Fig. 6.

Fig. 7

FIG. 1 is a front perspective view of an electric dry shaver showing my new design;

FIG. 2 is a top plan view thereof;

FIG. 3 is a side elevational view of the shaver as seen at the left of FIG. 4;

FIG. 4 is a front elevational view of the shaver;

FIG. 5 is a bottom view of the shaver;

FIG. 6 is a side elevational view as seen at the right of FIG. 4; and

FIG. 7 is a rear elevational view.

I claim:

The ornamental design for an electric dry shaver, substantially as shown and described.
